THIN-FILM WINDOW DEVICE

Jerrold M. Seehof, Gardena, Melvin S. Armstrong, Lomita, and Stuart B. Smithberg, Inglewood, Calif., assignors to The National Cash Register Company, Dayton, Ohio, a corporation of Maryland
Filed Dec. 23, 1957, Ser. No. 704,532
13 Claims. (Cl. 313—74)

This invention relates to thin-window devices for scientific and other apparatus, and more particularly to thin-window devices which are permeable to streams or beams of low-energy electrons and which may be of relatively large diametral dimension and which can successfully withstand a pressure differential of the order of one atmosphere.

It is known that a gas-tight window device permeable to low-energy electrons, i.e., those of energies of the order of twenty thousand volts or less, and capable of withstanding one atmosphere of pressure differential, would be useful in a variety of industrial and scientific applications; and many attempts have been made to produce a window of the stated characteristics. Especially desirable has been a window of relatively large length and width, that is, of relatively large diametral dimension, with the aforesaid strength and electron permeability. For example, as indicated by U.S. Patents No. 2,616,961 and 2,630,484 to J. Groak, such a window device would make practicable an ultra-high speed printer by eliminating the impracticable operation of the paper-handling structures in an evacuated chamber.

As another example of the indicated utility of a window of the stated nature, there may be cited an apparatus for "electronic" photography, such as is disclosed in "Scientific American" magazine, March 1956, pages 81, 82, 84, 86, 88, and 90. In the latter apparatus an optical image of a region of outer space is focused upon a photocathode located in a high-vacuum chamber, and the electron emission from the photocathode is focused upon a photographic plate. In that particular apparatus, practical considerations require passage of the electron stream through a thin-film window situated between the photocathode and the photographic plate; but the thin-film window therein used must be well protected against any appreciable pressure differential. Hence that thin film is initially sealed in the high-vacuum chamber, protected by a "breakaway" cap which is not broken until a chamber containing the photographic plate is evacuated to a high vacuum. In that device, the thin-film window serves mainly to prevent contamination or "poisoning" of the photocathode by substances evolved by the plate and its coating; and the apparatus is not reusable.

The prior art offers considerable evidence of the long-felt need of an electron-permeable window device of the character indicated, and further portrays the results of a series of futile efforts to solve the problems incident to production of a satisfactory device. The U.S. patent to Knoll, No. 2,263,733 presents a lengthy list of desired results in respect of electron-permeable windows, and is replete with suggestions as to how the results were expected to be attained. This indicates that as early as 1929 the need for a pressure-resistant window was evident. Later art, such as U.S. Patents 2,004,176, 2,373,661, and 2,617,953, shows a continuing unfilled need for a window of the type described. That none of the prior art suggestions or teachings resulted in a practical window is made evident by the recent intensive research directed toward provision of a practical cathode ray tube window. The above cited article in the March 1956 issue of "Scientific American" magazine is pertinent in this respect.

2

It is evident, then, that a gas-tight electron permeable thin-film window capable of withstanding an atmosphere of pressure differential would greatly simplify the apparatus and procedures connected with the operations of the exemplary systems mentioned, and would permit or facilitate a wide variety of other research and scientific investigations. Accordingly, it is a principal object of the invention to provide an electron-permeable gas-tight thin-film window device of relatively large transverse dimensions and capable of withstanding a pressure differential of the order of one atmosphere.

A subsidiary object of the invention is to provide an electron-permeable gas-tight thin-film window device capable of withstanding a pressure differential of the order of one atmosphere at temperatures of the order of 500° C.

Another object of the invention is to provide a gas-tight electron-permeable thin-film window device capable of operating at relatively high temperature.

Other objects and advantages of the invention will become apparent or be made evident in the appended claims and ensuing description of a preferred embodiment of apparatus according to the invention as illustrated in the accompanying drawings, of which:

FIG. 1 is a partly schematic diagram of a cathode ray tube incorporating a window device according to the invention;

FIG. 2 is a fragmentary sectional view showing a window device according to the invention as employed in a "printing" apparatus;

FIG. 3 is an "exploded" view of principal parts of an exemplary assembly adapted to form an insert type of window device according to the invention;

FIG. 4 is a magnified representation of a small rectangular section of an exemplary matrix and thin-film according to the invention, with a portion of the thin-film removed to illustrate matrix details; and

FIG. 5 is a view, partly in section and with a portion removed, of a device incorporating and utilizing a form of electron-permeable thin-film window according to the invention.

In the drawings there is illustrated a preferred but exemplary form of dimensionally large thin-film window device capable of withstanding a pressure differential of the order of at least one atmosphere and permeable to low-energy electrons. By dimensionally large it is meant that the effective window opening may be at least two centimeters in length and width, or at least two centimeters in diameter. By a pressure differential of the order of one atmosphere is meant a difference in fluid pressure on opposite faces of the thin-film of the window device of from one-half to one and one-half atmosphere; one atmosphere being defined as approximately 1033 grams per square centimeter.

Referring to FIG. 1, a window device according to the invention is shown as applied to the target end of an exemplary type of cathode ray tube 20. The evacuable vessel or envelope 21 of the tube may enclose a source of electrons such as an electrically heated filament 22, conventional electron-accelerating and electron-beam-shaping means such as is indicated at 23, electron-beam deflection means such as vertical and horizontal electrode pairs 24 and 25. The pairs of deflecting plates may be provided with sealed leads such as 24a, 25a, respectively, for application of beam-deflecting potentials; and the tube may be provided with other conventional control means such as a magnetic focusing and deflection means (not shown). Envelope 21 includes an end wall 21a which may be of conductive metal or of conductively coated glass as in conventional cathode ray tubes. The end wall is provided with a suitable aperture in which a win-

dow device according to the invention is shown suitably sealed.

Referring now to FIGS. 2, 3 and 4, details of construction of a preferred exemplary form of window device will be explained. The electron-permeable portion of the window device consists essentially of a thin but strong film-supporting matrix 30, preferably of strong heat conductive material such as metal, to which is secured an extremely thin-film of an electron-permeable material. The matrix of film-supporting element may be of any of a variety of forms, but preferably is of very fine metal mesh, electroformed or woven. An exemplary suitable mesh is 80 count nickel-copper "Lektromesh" marketed by C. O. Jellif Corporation, Southport, Connecticut. The electron-permeable thin-film which is supported by the matrix and which may, for example, be of the order of eighty micro-inches thick, is substantially impermeable to atmospheric gases, and with its supporting matrix is capable of withstanding a pressure differential of the order of one atmosphere. The preferred mode of producing a window device as exemplified in FIG. 1 comprises the following steps:

(1) The matrix or mesh 30, in the form of a disc (FIG. 3), is pressed into a flanged electrically conductive mount 27 by an internal metallic ring 31 which forms a close fit with the mesh in the mount, as indicated in FIG. 2. The mounting is analogous to mounting a piece of cloth in an embroidery hoop, and the result is that the mesh is firmly supported about its periphery and is taut.

(2) The mounted mesh is thoroughly and carefully cleaned, as by using trichloroethylene followed by detergent and hot water and distilled water baths, in an ultrasonic cleaner device; and the assembled components dried.

(3) A commercial 3% aqueous dispersion (by weight) of sodium bentonite gel is diluted to a .4% dispersion with distilled water, and the dispersion very carefully spread over the exposed portion of the mesh. Care is exercised to make certain that all openings in the mesh contain a film of the dispersion.

(4) The mounted and coated matrix is placed under cover and carefully dried. A drying period of considerable duration, as forty hours, may be necessary for proper drying.

(5) The mount, matrix and coating or film are carefully baked; for example, eight hours at 315° C.

(6) After cooling, the peripheral areas of the device are sealed, as with "Pyseal" or apiezon wax, to insure gas-tightness between ring 31 and mount 27.

The window device is most conveniently applied to the tube end wall 21a by partial insertion in the aperture formed in the wall, a hardening sealant being employed as indicated at 32 (FIG. 2) and the flange of the mount being pressed against the exterior face of the end wall so that a firm and gas-tight support is secured. Thereafter the vessel may be evacuated, as by way of the tube 29 (FIG. 1). As indicated in FIG. 4, in which a small section of a completed device is shown considerably magnified and with a portion of the thin-film removed, the exemplary matrix 30 is a foraminous sheet-like structure produced by electro-forming and having clear openings or apertures 30a therethrough. The openings as depicted are of generally square configuration, and form passages through which low-energy electrons pass prior to passage through the thin-film which extends across the openings in the matrix. The matrix may be of other configurations than the exemplary form shown, but preferably provides a substantially planar support for the thin-film. The latter, as depicted at 33 in FIG. 4, is of the order of eighty micro-inches thick and is composed of the ceramic remainder left upon baking of the dried clay gel.

It is evident that some electrons of a beam directed at the thin-film window device installed in an envelope such as tube 20 will impinge upon the matrix rather than passing through an opening, and for this reason the matrix

preferably is made electrically conductive either by being formed of conductive material or by being given a conductive coating, whereby the charge of the intercepted electrons may drain away. As hereinafter explained in connection with FIG. 2, an electron-attracting device may be employed to enhance passage of electrons through the openings in the matrix. The end portion of the tube, such as end wall 21a, is insulated from the anode voltage of the tube. That portion of the electron beam which passes through the thin-film may be made intense enough to produce desired effects. To that end, an intense beam may be produced. Such a beam may produce considerable heating effect in the thin-film and matrix, and in fact may heat those elements to a dull red glow. However, the thin-film, being of ceramic nature, is capable of enduring such treatment without being harmed; and the film support or matrix, when made of nickel-clad copper, is capable of carrying away the heat to the end wall of the tube (which may be metallic) and of radiating a considerable fraction of the heat. Thus the matrix may perform the triple role of supporting the thin ceramic film, draining away intercepted electrons, and acting as a heat conductor; while the thin-film not only permits passage of electrons, but excludes gas under a pressure differential while operating at a fairly high temperature.

As illustrated in FIG. 2, the window device is adapted to pass an electron beam, either in relatively fixed form or as moved or "deflected" by potentials applied to plates such as 24, 25 of the tube 20 (FIG. 1), directly onto a surface placed in close proximity to the window device. For example, as indicated, the beam may be directed to pass through the window device and onto a moving sensitized film or record medium 35. Also, passage of electrons through the window and onto the target may be enhanced by applying an attracting potential to the target if it be conductive, or by providing a positively charged plate in back of the target if the latter is not conductive. For example, as indicated in FIG. 2, a conductive plate 34 may be placed in close proximity to the target opposite the window, and connected to a source of potential as indicated, whereby electrons are attracted through the window and drawn to the film or target. The film is, for clarity of illustration, shown somewhat displaced from the thin-window device surface; however, in practice the film or other "target" may be disposed substantially in contact with the window device. Under some circumstances it may be desirable to delimit the areal cross-section of the beam passed through the window, and this may be done, in instances, by so focusing the beam that substantially all of it passes through a single opening of the matrix, using known beam-focusing means and techniques. In other instances, as where a predetermined pattern or trace-configuration is to be produced on the target by the beam (as, for example, in "printing" a specific predetermined character on a beam-sensitive film), the beam may rapidly be deflected to-and-fro across the window, and intermittently suppressed, while the target or film is traversed past the window in a direction transverse to that of the beam deflection; and in such instances the beam may be of a selected density and cross-section to suit the circumstances. In the particular usage illustrated in FIG. 2, the beam-sensitive record medium 35, in the nature of a strip film, is drawn from a supply 35s over a guide 36 and past the window device by a driven draw roll 37, from which it passes to suitable means such as a receiver-roll 38. The record medium is "exposed" by the electrons passed through the window device; and it is understood that it may be "developed" if necessary, by conventional procedure and means (not shown) on its way to roll 38.

Any suitable evacuable vessel may be fitted with a window device of the character described, and any suitable source of electrons may be utilized. As indicated in FIG. 5, a window device 40, similar to that previously described and explained, is shown installed in a thick-

walled vessel 41 which is evacuable as by way of a tube 42. Within the vessel is situated a source of radiation in the form of a radioactive mass 43 which is depicted as being adhesively secured to the inner wall or surface of the vessel. The vessel may be of suitable radiation-absorbing material, such as lead, and of a thickness to prevent undesired radiation to exit from the vessel through other than the window device. Similarly, the mount and ring of device 40 may be made of a like material to thus substantially restrict exiting radiation to the area of the thin-film and matrix.

From the preceding description and explanation it is evident that the invention comprehends and provides a gas-tight window device comprising essentially a supporting matrix having opposed faces of large dimensions relative to its thickness, and a thin electron-permeable ceramic film supported by the matrix and adapted to withstand at least one atmosphere of pressure differential. While the matrix is shown as one having large transverse dimensions, that is, of large diametral dimensions, it is clear that the window device may equally well be in the form of a long narrow structure. Also, in view of the preceding explanation and description of a preferred exemplary embodiment of the invention, other changes and modifications within the spirit and scope of the invention will occur to those skilled in the art; and accordingly it is not desired to be limited to the specific details of the described structure.

What is claimed is:

1. A substantially gas-tight window device adapted for use as an electron-permeable element of an evacuable vessel, comprising, in combination: a support presenting a transverse opening therethrough from face to face thereof; and thin non-vitreous ceramic means permeable to low-energy electrons and substantially impermeable to gas under a pressure differential of the order of one atmosphere, closing said opening.

2. A gas-tight window device adapted for use as an element of an evacuable vessel, comprising, in combination: a foraminous support of large face dimensions relative to its thickness and presenting a plurality of generally transverse openings therethrough from face to face thereof; and thin non-vitreous ceramic film means permeable to low-energy electrons and substantially impermeable to gas under a pressure differential of the order of one atmosphere, closing said openings in said support.

3. Apparatus for providing a beam of electrons outside an evacuable vessel, comprising: an evacuable vessel having a wall with an aperture therein; a source of low-energy electrons in said vessel; a window device forming a substantially gas-tight closure for said aperture and consisting essentially of a thin gas-tight electron-permeable non-vitreous ceramic film and a support matrix having a plurality of openings therethrough from face to face and all of the openings of which are closed to passage of gas therethrough by the thin ceramic film; and electrode means outside said vessel and positioned closely adjacent said window device, for attracting electrons through the openings of said matrix.

4. Apparatus according to claim 3, said matrix comprising electrically conductive material.

5. Apparatus according to claim 4, said film comprising essentially a substance capable of withstanding an operating pressure differential of the order of one atmosphere applied across the faces of the window device.

6. Apparatus according to claim 5, the substance of said film being of baked ceramic material capable of operating at a temperature of the order of 500° C.

7. Apparatus according to claim 6, said vessel having at least said wall made of metal.

8. An evacuable vessel having a wall and comprising: a gas-tight window device sealed in an aperture in the

wall of said vessel and comprising as essential parts a support and thin-film means, said support presenting opposite faces of large dimensions relative to its thickness and having a plurality of openings therethrough from face to face, and said thin-film consisting essentially of a thin non-vitreous ceramic film permeable to low-energy electrons and impermeable to gas under a pressure differential of the order of one atmosphere and closing said openings, whereby low-energy electrons may pass through the aperture in the wall of said vessel and gases prohibited entry thereto, while the vessel is evacuated.

9. A device according to claim 8, said support comprising metallic material adapted to readily conduct heat and electric charges produced by intercepted electrons.

10. A device according to claim 9, said ceramic material being capable of operating to pass electrons and exclude gas while at a temperature of the order of 500° C.

11. A device according to claim 9, said device including a rigid metallic mount in which said support is fixed.

12. An apparatus for supplying a stream of electrons including low-energy electrons to a readily accessible target outside an evacuable vessel, comprising, in combination: an evacuable vessel comprising a wall having an aperture of large transverse dimensions therein; means for supplying a stream of electrons including low-energy electrons for passage through said aperture from the interior to the exterior of said vessel while the latter is evacuated; a gas-tight window device sealing said aperture against entry of gas but permitting exit of electrons including low-energy electrons through the device, said device comprising a foraminous support of large transverse face dimensions sealed in said aperture and presenting a multiplicity of unobstructed openings extending

35 directly therethrough from face to face, and said device also comprising non-vitreous ceramic thin-film means permeable to low-energy electrons and effectively closing said openings against passage of gas under a pressure differential of the order of one atmosphere; electrode means outside said vessel and closely adjacent said window device for attracting electrons through the openings of said support; and said apparatus also including means by way of which said vessel may be evacuated; whereby a stream of electrons directed toward said window device

45 from the interior of said vessel is at least in part passed through said thin-film means for collision with a target placed between said window device and said electrode means.

13. Apparatus according to claim 12 said support being in the form of a heat-conductive matrix of electrically conductive metal.
